UNITED STATES PATENT OFFICE.

EDWARD KENER, JR., OF BUFFALO, NEW YORK.

COMBINATION RANGE.

1,409,344.

Specification of Letters Patent. Patented Mar. 14, 1922.

Application filed November 28, 1919. Serial No. 341,153.

To all whom it may concern:

Be it known that I, EDWARD KENER, Jr., a citizen of the United States, residing in Buffalo, in the county of Erie and State of New York, have invented new and useful Improvements in Combination Ranges, of which the following is a specification.

This invention relates to a cooking stove or range which may be heated either with 10 gas or with a solid fuel.

The object of the invention is to provide a combination range which, with a maximum thermal efficiency, may be used continuously with either of the kinds of fuel, 15 without impairing the efficiency of the range for use with the other kind of fuel.

A more specific object of the invention is to provide a range construction which will permit of heating all sides of the oven and 20 also permit of a down draft of the spent gases, when using either form of fuel.

A further object of the invention is to provide a combination range in which the 25 flue dust from the fire box may be passed directly over the gas burners without clogging the orifices of said burners.

A further object of the invention is to provide a gas burner which may be readily inserted or removed without requiring any 30 special tools or experience.

A still further object of the invention is to provide for automatically altering the flue or vent arrangement of the range upon placing in position certain members which are 35 only used in the range when the one kind of fuel is to be burned.

Further objects and advantages of the invention are more clearly disclosed in the following specification and accompanying 40 drawings wherein:—

Figure 1 is a diminutive perspective of the entire combination range. Figure 2 is a diminutive vertical transverse section thereof with the flame spreader plate removed and 45 the oven burner covering door in its lowered position. Figure 3 is a similar vertical transverse section through the range taken on line 3—3, Fig. 1. Figure 4 is an enlarged top plan of the gas burner and its 50 apertures, taken on line 4—4, Fig. 3. Figure 5 is a horizontal section through the range taken on line 5—5 Fig. 3. Figure 6 is also a horizontal section through the range with parts broken away and taken on line 55

6—6, Figs. 3 and 7. Figure 7 is a vertical 55 longitudinal section through the range taken on line 7—7, Fig. 3.

Similar characters of reference refer to like parts throughout the several views.

10 represents the usual form of fire box 60 which is lined with suitable fire brick 11 and is provided with the usual grate bars 12 and ash pit 13. Against the inner vertical wall of said fire box 10 is arranged a cooking oven or heating compartment 14 in which 65 are placed such partly prepared foods as must be heated from all sides to properly cook or bake the same.

Extending over the upper part of both 70 said heating compartment 14 and said fire box 10 is a gas burner or combustion chamber 15, which communicates directly with the upper part of said fire box 10 as shown in Fig. 7, but is separated from the heating compartment 14 by an oven roof plate 16. 75 The one end wall of the gas-burner compartment 15, which is adjacent to the upper end of the fire box, is provided with a suitable air inlet shutter 17, which may be opened when it is desired to feed air to the upper 80 surface of the solid fuel in said fire box 10 so as to produce a down draft therethrough. The gases of combustion in such case pass through the fire box 10 and out of the ash pit 13 through a down-draft valve 18 and 85 thence into the lower part of a flue back 20, as shown in Fig. 6, which is arranged vertically on the rear part of the range and connects at its upper end with the usual smoke or outlet pipe 21. 90

When it is desired to obtain a hotter fire in the fire box or when adding fresh fuel thereto, this down-draft valve 18 may be either partly or wholly closed, and an up-draft, an air inlet shutter 22 opened the 95 proper amount, which allows pure cold air to be drawn therethrough from the outside of the range. This air is properly pre-heated by being caused to impinge against the outer hot face of the end fire brick lining 100 110, the air then continuing downwardly to the ash pit where it is deflected upwardly through the grate bars 12 and into the bottom of the bed of solid fuel. This pre-heating of the air causes a complete hot combustion of the solid fuel without any tendency to chill the lower exposed points of 105 said fuel and thereby prevent the complete

combustion of the same as ordinarily occurs when the air which is fed to the solid incandescent fuel is not preheated.

Arranged above and closely adjacent to the roof plate 16 of the heating chamber 14, are a plurality of gas burners 23 which extend through the front vertical wall 24 of the range and are fed from a common gas fuel pipe 25, the flow into each gas burner being suitably controlled by an individual gas valve 26. A novel means is employed in this improved range whereby each of said gas burners may be quickly and easily removed whenever desired from said range, the arrangement being as follows:

Secured to each of said gas valves 26 is a rearwardly extending gas nozzle 27 which is adapted to fit loosely into a suitable gas nozzle engaging hole 28. This hole is formed centrally in the forward end of its companion gas burner and acts to prevent lateral displacement of said gas burner. Formed at the forward end of each gas burner and positioned rearwardly of said engaging hole 28, is an enlarged annular collar 30, which is greater in diameter than any of the parts of the gas burner which lie forwardly of the same. Each collar 30 is adapted to be received within a suitable hole 31 which is formed in the vertical front wall 24 of the range. Formed on each gas burner at the rear end of said collar 30 is an outwardly extending annular flange 32 which is adapted to bear against the rear face of the vertical front wall 24 of the stove aforesaid and thereby limit the forward movement of the gas burner as the same is moved outwardly into its position through the said hole 31. Formed on the lower face of each gas burner at the rear or inner end thereof is a pair of downwardly projecting retaining lugs 33 which are positioned transversely with respect to each other but each of which extends longitudinally of the gas burner and is provided on its lower edge with an upwardly extending transverse groove or concave notch 34. Adapted to be loosely received by the concave notch 34 are a pair of transversely disposed supporting posts 35 which are formed on the upper face of the oven roof plate 16. Thus the rear end of each burner is supported a suitable distance above said roof plate 16 of the heating compartment 14 which thereby avoids any undue scorching of the area immediately below the gas burner. The concave notch 34 also aids in longitudinally positioning the burner and prevents the same from moving rearwardly out of position. The front end of each gas burner is provided with an air mixing valve 36 of the usual type which by reason of its injector action mixes a sufficient amount of air with the gas that issues from the gas nozzle 27. Added or auxiliary

air is also fed directly to the gas burners at the point where the flames issue from the small orifices 38 of the gas burner proper. This auxiliary air may if desired be fed through the air inlet shutter 17, which is arranged at one end of the stove as aforesaid, but it is preferred that said auxiliary air enter the combustion chamber through an air inlet hole 40, which is formed in the vertical end wall of the stove immediately adjacent the outer end of the heating compartment. This air inlet hole 40 communicates directly with the outer air and with the adjacent end of the gas burner chamber 15 and is controlled by a suitable control gate 41 which is provided with a suitable exterior operating handle 42.

At the rear end of the gas burner chamber and adjacent to the inner or central end of the heating compartment 14 is arranged a common flue opening 43 which communicates outwardly with the upper part of the flue back 20 and communicates inwardly with the aforesaid gas-burner chamber. The flow of the gases of combustion through said flue opening 43 is controlled by a suitable swinging flue-opening valve 44, which when in its open position (as indicated by dotted lines) permits the spent gases from either the fire box 10 or from the gas-burner chamber 15 to pass directly into the flue back and thence into the usual smoke or outlet pipe 21. Arranged below the control gate 41 and between the vertical outer or end wall 60 of the heating compartment 14 and the adjacent vertical end wall of the range is a circulating channel 45, which extends vertically downwardly and thence horizontally inwardly under said heating compartment 14 and communicates permanently with the lower end of the flue back 20 through a suitable exhaust opening 46.

Projecting forwardly and outwardly from the floor 47 of the heating compartment 14 is a suitable detachable oven shelf 48 in the upper rear surface of which is recessed a longitudinal oven heating gas pipe 50. The latter is suitably connected by means of a feed gas pipe 51 with the gas supply line 52 and a plurality of longitudinally arranged gas holes or burning apertures 53 are drilled in the upper, inner longitudinal face of said heating gas pipe 50, as best shown in Figs. 3 and 6, the burning gas flames which issue therefrom being adapted to directly heat the interior of said oven or heating chamber 14, the spent gas passing out of said heating chamber through an oven vent 54 into the lower part of the aforesaid flue back 20. Detachably resting on the floor 47 of the heating compartment and also resting with its forward end on the upper side of the oven shelf 48, is a flame spreading plate 55. The forward end of said spreader plate extends the full width of the heating compartment 130

and is adapted to completely cover up both the oven heating pipe 50 and also the recess 56 which receives the same, while the rear end of said flame spreading plate is considerably narrower than the heating compartment. Air enters the oven through an air feed aperture 57 which is formed in the oven shelf below the heating pipe recess 56 and after being heated by the aforesaid oven 10 heating pipe 50, passes horizontally rearwardly under said flame spreading plate 55 and some of said heated air is permitted to flow laterally against the side vertical walls 60 and 600 of the oven and thence upwardly 15 between said oven walls and the adjacent parallel edge 61 of the flame spreading plate 55. The rest of the heated air coming from beneath the flame spreading plate 55 continues directly rearwardly from the oven 20 heating pipe 50 and strikes against the vertical rear oven wall 601, passing thence up into the oven proper, between said rear oven wall and the rear parallel edge 64 of the flame spreading plate. The heated air passing 25 up and around the rear and side edges of the flame spreading plate turns inwardly toward the center of the heating oven and strikes all sides of any pans or dishes of food which are being heated in the oven. By 30 reason of the fact that the oven vent 54 is located well toward the bottom of the oven the cooler convection currents of heated air are caused to pass downwardly against the top surface of the food which is being prepared in the oven, so that said food is thoroughly and uniformly heated from each and 35 every side resulting in an even, thorough cooking or baking of the same.

Provision is also made for preventing the 40 flames of the oven heating pipe 50 from striking directly against the bottom face of the flame spreading plate 55. This is accomplished by securing a flame striking plate 66 to the lower face of said flame spreading 45 plate 55 in spaced relation thereto and just above the oven heating pipe, so that the air space between the two plates, being a non-conductor of heat, prevents the direct intense heat of the oven heating plate from scorching 50 the flame spreading plate. When solid fuel is being used in the range, the whole flame spreader plates 55 together with its appurtenances, may be entirely removed from the heating compartment. This operation 55 automatically permits an oven vent door 67 to swing downwardly and forwardly into the position shown in Fig. 2, thereby closing the oven vent 54. When the flame spreading plate 55 is in position in the heating 60 compartment it acts to hold rearwardly open the said oven vent door 67, by reason of a longitudinal push rod 68 which is secured to the lower face of the flame spreading plate and which is adapted to push open 65 said oven vent door with its rear end or tip

portion. As the flame spreading plate is only employed when gas is being used, it is seen that the operation of the oven vent door 67 is entirely automatic, its position being governed solely by the presence or absence of the flame spreading plate aforesaid. 70

When the said flame spreading plate 55 is first removed, the recess 56 and the oven heating pipe 50 are both exposed. To cover the same, a covering door 70 is hinged to 75 the inner side of the main oven door 71 at the lower forward corner thereof. When the flame spreading plate is in position in the oven said covering door 70 is turned up and back and is secured in its raised position by a suitable latch 72 which is pivoted to said oven door at 73. When however, it is desired to burn coal in the range, the flame spreading plate 55 is removed from the oven and the covering door 70 is dropped into 80 the position shown in Fig. 2, the opposite ends of the covering door 70 resting on suitable projecting shelves 74 which are formed on the lower edge of the oven door and project horizontally rearwardly therefrom. 85 Thus when the oven door is closed, the said covering door covers the oven heating pipe 50 and its recess 56 and also prevents any air from entering the oven through the air feed aperture 57 which is situated immediately 90 below the said oven heating pipe. 95

The operation of the combination range is as follows, referring particularly to Fig. 7:

When gas is being used as a fuel in the range, the control gate 41 is dropped into 100 the position shown in the drawings thereby permitting pure air to enter the gas burner chamber 15 through the inlet air hole 40. If the oven or heating compartment 14 is not to be used and a very intense heat against 105 only the top of the stove is desired, the flue opening valve 44 is swung back into the dotted line position thereby allowing the gases of combustion from the gas burners 23 to pass directly into the flue back 20 and thence 110 up the smoke pipe 21. If however, it is desired to heat the said heating compartment 14 and to obtain a down draft of the gases of combustion, this flue-opening valve 44 is closed and the down draft slide valve 18 is 115 opened. This allows some of the hot gases of combustion from the gas burners to flow downwardly into the fire box 10 and the ash pit 13 and thence out through said down draft valve 18 into the bottom of the flue 120 back 20, thereby heating that end 600 of the oven which is adjacent to said fire box. The rest of the hot gases of combustion flow downwardly through the cut away portions 410 of the control gate 41, as indicated by arrows Fig. 5, and into the circulating channel 45 around the baffle plate 76 and finally out into the lower part of the flue back 20 through the exhaust opening 46, thus heating 125 the top and bottom and also the end wall 130

60 of the heating compartment 14 aforesaid. When it is desired to obtain a very high temperature in said heating compartment, gas through the oven heating pipe 50 is turned 5 on and ignited through a suitable ignition hole 77, air being fed to said heating pipe through an air feeding aperture 57 arranged below said pipe. The hot gases of combustion emanating from said oven heating pipe 10 strike directly against the flame striking plate 66 and thence pass under a flame spreading plate 55 which is suitably supported a short distance above the floor of the heating compartment. The said hot gases 15 then flow against the rear and two side walls of the heating compartment and are then deflected upward between said heating compartment walls and the edges of said flame spreading plate 55. The cooler gases in the 20 heating compartment then descend and pass into the lower part of the flue back through the oven vent 54, which is controlled by an air oven vent door 67.

When solid fuel is to be used in the fire 25 box 10, the flue opening valve 44, and the up-draft air inlet shutter 22 are opened when starting the fire or when adding a considerable amount of new fuel, as is common practice in coal ranges. When the fire is to 30 be checked however, this flue-opening valve 44 is closed and the down draft slide valve 18 and also the air inlet slide valve 17 are opened, thereby causing the hot gases of combustion to pass downwardly through 35 said slide valve 18 and thence into the lower part of the flue back 20. When it is desired to heat the oven or heating compartment 14, the said down draft slide valve 18 is closed and the up-draft air inlet shutter 22 40 is opened and the control gate 41 thrown up into the dotted line position. This causes the hot gases of combustion from the fire box to heat the entire top of the stove, by traversing the entire length of the gas-burner 45 chamber 15, and to pass thence downwardly into the circulating channel 45 and out into the lower part of the flue back 20 through the exhaust opening 46. This causes a heating of both ends and top and bottom of the 50 heating compartment (and also the rear wall thereof by reason of the proximity of the said flue back 20). When the oven is thus being heated with solid fuel in the fire box 10, the flame spreader plate 55 is removed 55 together with its appurtenances which removal automatically closes the oven vent door 67 by reason of the fact that the same is held open by the longitudinal push rod 59 when the flame spreading plate 55 is in 60 position. When said spreader plate 55 is not being used, the latch 72 is turned and the cover door 70 is dropped down on to

the oven-door shelves 74, so that when said oven door is closed, the said cover door covers up the oven heating pipe 50 and prevents any air from entering the air feed aperture 57 which is located directly beneath said heating pipe, thereby making the whole oven air tight when using solid fuel. 65

It is manifest that this combination range 70 permits of maximum flexibility and efficiency when burning either gas or a solid fuel, without necessitating a sacrifice for one in behalf of the other. Either an up draft or an efficient down draft may be 75 obtained when burning either kind of fuel and the heating compartment or oven may be uniformly heated in either case. When using a solid fuel on the up draft, a partial vacuum is created in the gas-burner chamber 15, which acts to suck pure air from the air mixers 36 of the gas burners through the small orifices 38 of said gas burners thereby preventing any accumulation of dust or soot in these orifices. At the same time, 80 85 a diluted wide area current of fresh air is drawn into the hot gases of combustion which acts to completely oxidize any partially oxidized gases of combustion, whereby the foul odored and poisonous qualities of 90 the flue gas are changed so that the gas passing into the flue back is not only odorless but non-poisonous as well. It is obvious that this combination range and a number of the novel features thereof may be employed in 95 the construction of garbage incinerators, burning ovens for painted and glazed crockery, metal annealing ovens, rendering ovens and divers other uses. 100

I claim as my invention:

1. A combination range comprising a heating compartment provided with a door, an outer oven shelf arranged in front of said heating compartment, an oven burner recessed in the upper face of said outer oven 105 shelf, a flame spreading plate engaging with said shelf and extending rearwardly over said oven burner, and a covering door pivoted to the oven door and adapted to cover said recessed oven burner when the flame 110 spreader plate has been removed.

2. A combination range comprising a heating compartment, an outer oven shelf, an oven burner recessed in said shelf, an oven door adapted to swing over said oven burner, a covering door hinged to said oven door and adapted to cover said recessed oven burner when in its lowered position, a removable flame spreader plate arranged above said oven burner, flame channels at the rear 115 end and sides of said spreader plate, and a flame striking plate arranged below said spreader plate in spaced relation thereto. 120

EDWARD KENER, JR.
